LAWRENCE WHITCOMB, OF BROOKLINE, MASSACHUSETTS, ASSIGNOR TO THE CORK
INSERT COMPANY, OF BOSTON, MASSACHUSETTS, A CORPORATION OF MAINE.

PULLEY.

1,156,120.

Specification of Letters Patent.

Patented Oct. 12, 1915.

Application filed December 18, 1911. Serial No. 666,391.

To all whom it may concern:

Be it known that I, LAWRENCE WHITCOMB, a citizen of the United States, residing in Brookline, county of Norfolk, and State of Massachusetts, have invented an Improvement in Pulleys, of which the following description, in connection with the accompanying drawings, is a specification, like letters on the drawings representing like parts.

This invention relates to pulleys of that class having a thin or substantially thin metal circumferential rim portion, either circular or conical in form, and has for its object to increase the frictional efficiency of pulleys of this class, without materially increasing the weight and cost of the same, whereby a light and efficient pulley is obtained, which is especially adapted among other uses to be employed on spinning

frames, cotton pickers and like machines. To this end, the thin metal rim of the pulley is provided with a plurality of holes or openings through which are extended inserts of cork or other non-metallic material, which have their outer ends flush or substantially flush with the outer circumference of the metal rim, and their inner ends extended into sockets formed in a center or body portion of plaster of Paris or other light, non-metallic material, which is normally in a plastic condition, so that it can be molded or packed or tamped within the metal rim and allowed to harden thereon, and which is retained therein by suitable retaining walls.

Figure 1 is a plan view of two pulleys or speeder cones embodying this invention, and belted together after the manner common to spinning frames. Fig. 2, a longitudinal central section of the concaved conical pulley shown in Fig. 1, the section being taken on the line 2—2, and Fig. 3, a cross section of the convexed conical pulley shown in Fig. 1.

In the present instance, I have shown the invention as embodied in conical pulleys *a*, *b*, connected by a belt *c*, one of said pulleys as *a* being concaved and the other as *b* being convexed, said pulleys being such as are now commonly used in spinning frames and known as the speeder cones thereof. These cones in the operation of the spinning frame play an important part, and it is highly desirable that the belt *c* should slip as little as possible, so as to avoid slackening of the tension on the roving, which results in variation of the twist and uneven weight in

the roving, and if this slackening is excessive, the roving becomes tangled, which requires stopping of the spinning frame and resetting of the cone belt *c*.

The cone belt tension is fixed by the weight of the lower cone *b* and its cradle (not shown), consequently any variation of slip of the belt *c* must come from the condition of the surfaces of the cone pulleys *a*, *b*, and in practice a slip of over 3% is sufficient to cause the troubles above noted. The elimination of slip on speeder cones is most desirable as there is obtained thereby, a more even roving with less readjustments of the machine, such as resetting of cone belt, changing tension gear and changing "lay" gear. The present invention has for its object to provide a construction of pulley, which can be incorporated in speeder cones, so as to avoid the difficulties above noted and thereby obtain the superior results above noted. To accomplish this result, the pulley is provided within it with a body *f* of non-metallic material in plastic form, such for instance as plaster of Paris, which body is molded, tamped or pressed into the interior of the pulley against a retaining wall, which is shown in Fig. 3 as composed of an annular flange 10 on the inner circumference of the metal rim and a collar 12 secured to said flange and mounted on a shaft 13.

The plastic material preferably fills the interior of the cone about the shaft 13 as represented in Fig. 2, and after the pulley has been filled, the end of the pulley through which the plastic material is inserted is closed by a disk or plate 15, which is secured to an internal flange 16 on the rim of the pulley and forms a retaining wall for the plastic material, which is allowed to harden, and when hard, sockets 17 are formed in the body portion when the holes in the rim of the pulley are drilled, and the corks 18 are inserted under compression into said sockets, with their outer surfaces substantially flush or projecting slightly above the outer circumference of the rim. The collar 12 and disk 15 constitute one form of hub for the pulley.

The plastic non-metallic material is light and adds but little to the weight of the pulley, while it enables pulleys with thin rims to be provided with frictional inserts at a minimum expense and without adding materially to the cost of the pulley. Further-

more, the plastic material enables pulleys of small diameters and especially conical pulleys of small diameter at the apex portion of the cone, to be provided with cork 5 inserts, where otherwise it would be impracticable to use a normally rigid filler on account of the small diameter of the cone or pulley and further on account of the weight which would be added to the pulley.

10 Claims.

1. As an improved article of manufacture, a pulley having a substantially thin metal rim portion provided with a plurality of holes or openings extended through it, a 15 body of substantially light, normally plastic, non-metallic material, capable of being easily drilled and located within said rim and provided with sockets which register with the holes in said rim, retaining walls 20 for said normally plastic material within said rim, and inserts of cork forming part of the outer surface of said rim and extended through the holes in said rim into the sockets in the normally plastic material.

2. As an improved article of manufacture, a pulley having a substantially thin metal rim portion provided with a plurality of holes or openings extended through it, a body of substantially light non-metallic material capable of being easily drilled and located within said rim and provided with sockets which register with the holes in said rim, said material being normally plastic to enable it to be molded or pressed within the 35 rim of the pulley and capable of hardening when dried, means for confining the said plastic material within the said rim, and inserts of non-metallic material forming part of the outer surface of said rim and extended through the holes in said rim into said sockets.

3. As an improved article of manufacture, a pulley provided with a substantially thin conical metal rim having a plurality of holes 45 extended through it, substantially light non-metallic normally plastic material capable of being easily drilled and substantially filling the said conical rim and having a plurality of sockets registering with the

holes in said rim, retaining walls for said normally plastic material, said walls being located near the ends of the conical rim, and inserts of non-metallic material forming part of the outer surface of said rim and extended through the holes in said rim into 55 said sockets.

4. As an improved article of manufacture, a pulley having a substantially thin metal rim, a body portion of substantially light normally plastic material within said rim 60 capable of being easily drilled, and inserts of non-metallic material forming part of the outer surface of said rim and extended through said rim into said normally plastic material, substantially as described. 65

5. As an improved article of manufacture, a pulley having a substantially thin metal rim, a body portion of plaster of Paris substantially filling the space within said rim, and inserts of non-metallic material forming part of the outer surface of said rim and extended through said rim into said plaster of Paris body, substantially as described. 70

6. The combination with a machine element having a thin-shelled body portion, of a filling or lining of plastic material introduced into said body portion, holes being formed in the shell and pockets or seats extending into the said plastic material, and inserts occupying said holes and pockets or 80 seats with their outer ends exposed for frictional purposes.

7. In a cone-pulley, the combination with a thin shell forming the body thereof, of a filling or lining of plastic material, holes 85 being formed in the shell and pockets or seats extending into the said plastic material, and inserts occupying said pockets or seats with their outer ends exposed for frictional purposes. 90

In testimony whereof, I have signed my name to this specification in the presence of two subscribing witnesses.

LAWRENCE WHITCOMB.
